UNITED STATES PATENT OFFICE.

HENDEICUS BERNARDUS KRITHE, OF COEVORDEN, NETHERLANDS.

VAPORIZING APPARATUS FOR LIQUID-FUEL INTERNAL-COMBUSTION ENGINES.

No. 910,693.

Specification of Letters Patent.

Patented Jan. 26, 1909.

Application filed January 29, 1907. Serial No. 354,784.

To all whom it may concern:

Be it known that I, HENDEICUS BERNARDUS KRITHE, mechanical engineer, a subject of the Queen of the Netherlands, residing at No. 29 Bentheimerstraat, Coevorden, in the Kingdom of the Netherlands, have invented certain new and useful Improvements in Vaporizing Apparatus for Liquid-Fuel Internal-Combustion Engines, of which the following is a specification.

The present invention consists in a new vaporizing apparatus for liquid fuel internal combustion engines.

The new vaporizing apparatus consists substantially of a chamber which is arranged in the cylinder head, and is separated from the interior of the cylinder, and which is heated by the successive combustions of the combustible mixture in the cylinder, and in which, without the employment of a special "heat well", the admitted liquid fuel is partly or completely vaporized to a constant volume, and thereby acquires a pressure such as enables it to pass with an excess of pressure and in a finely vaporized condition into the interior of the cylinder, wherein the completely vaporized fuel serves to atomize completely any residue of liquid fuel which may be present therein in an unvaporized state.

The admission of the fuel is effected as follows:—A separate compression space situated in the cylinder head is in communication through a small passage with the interior of the cylinder and with an annular space arranged at the bottom of the said compression space, and this annular space communicates through a duct with the fuel supply duct in such a manner that a small quantity of fuel is drawn into the said annular space during the suction stroke. This fuel is compressed during the next following compression stroke in the vaporizing apparatus, and is vaporized with constant volume by the contact with its highly heated walls, while the unvaporized portion remains on the bottom of the same. By means of a positively operated valve the body of fuel which has become vaporized for the greater part and is under great pressure will pass into the interior of the cylinder, whereby the completely vaporized fuel will now completely atomize the unvaporized residue and then, as above stated, will be ignited by reason of the high temperature of compression obtaining in the interior of the cylinder.

The invention is illustrated by way of ex-

ample in a practical form in the accompanying drawings in which:—

Figure 1 is a longitudinal section through the apparatus, with a partial section through the piston and the cylinder head. Fig. 2 is a horizontal section on the line A—B of Fig. 1. Fig. 3 is a cross section on the line C—D of Fig. 1, and Fig. 4 is a cross section on the line E—F of Fig. 1.

In the cylinder head *a* the compression cylinder *b* is inserted and fixed in a suitable manner. It is constructed as a hollow cylinder with double walls, and consists substantially of a compression chamber *c* which communicates freely through the connecting pipe *d* and a duct *e* formed in the cylinder head, with the cylinder space *f* (Fig. 1).

The compression chamber *c* is encircled by the cooling jacket *g* through which flows water which is supplied by the pipe *h*, and flows away through the pipe *i* (Fig. 2).

The bottom of the compression chamber *c* is provided with four outer oblong apertures *j* which are annularly arranged around the axis of the compression chamber and which are separate from one another, and opposite to which are arranged four inner similar apertures *k* (Fig. 3). The apertures *j* and *k* are separated from one another by means of a downwardly extending partition *p*. There is further provided in the compression cylinder a fuel duct *l* (Fig. 2), which communicates at one end with a fuel supply pipe *m*, and at its other end with an annular space *n* situated at the bottom of the compression cylinder *b*. The annular space *n* is closed or bounded at its lower edge by an automatic valve *o* which has two valve seats, namely one on the partition *p*, and another on the lower lip of the annular space, so that by this means the apertures *k* and the annular space *n* with the apertures *j* can be opened and closed simultaneously. Normally the valve is closed by spring pressure against its seats.

Immediately adjacent to the compression cylinder there is a vaporizer *q* which is made of good heat conducting metal and has the shape of a hemisphere. It fits exactly in a bore of the cylinder head which flares or is bell-mouthed towards the cylinder, so that the vaporizer is freely exposed towards the interior of the cylinder. The vaporizing chamber *q* is further characterized by the provision of a hemispherical bowl-shaped vessel *r* which is fixed to the vaporizer by means of four ribs (Fig. 4). The compres-

sion cylinder is closed by means of a cover in which is guided in a suitable manner a valve spindle *s* which passes through the valve *o* and serves to close an aperture *t* in the vessel 5 *r*, and an aperture *u* in the vaporizer *q*. The spindle *s* is operated by means of a bell crank lever *2*, operated by a roller *3* and a valve gear disk *4*. As shown the free end of the lever *2* surrounds the spindle, the latter may 10 move in a casing mounted on the cover.

Between the fuel inlet pipe *m* and the fuel reservoir is inserted a non-return valve *v*.

In the middle of the piston *w* opposite the vaporizer *q* there is screwed a table-like 15 round plate *x*.

The duct *e* in the cylinder head *a* is arranged vertically, its lower end follows a parabolic course, and the exit aperture is determined and partly formed by a shoulder 20 or boss *y* in the cylinder head.

The manner of operation is as follows:— The position of the piston *w* shown in Fig. 1, is that of the dead center. As the piston moves down, a slight rarefaction of the air 25 takes place in the cylinder space *f*, and is transmitted through the duct *e* and the pipe *d* as far as the interior of the compression chamber *c*, and the annular space *n*. Consequently the non-return valve *v* opens a 30 little, and some fuel flows in from the duct *m* and through fuel duct *l* into the annular space *n*, where it collects between the bottom of the cylinder *b*, the valve *o*, and the partition *p*. It is to be assumed that there is still 35 a certain high pressure in the vaporizer *q* due to a previous compression and charge. As the piston moves down, air is drawn into the cylinder, and during the next following upstroke of the piston, the body of air is 40 compressed, and compression also takes place in the chamber *c*. At the end of the compression stroke the pressure in the chamber *c* has become so great as to exceed considerably that in the vaporizer *q*, whereupon 45 the valve *o* opens automatically and some compressed air is blown into the vaporizer *q*. The fuel contained in the annular space *n* is then carried away by the compressed air 50 which passes partly through the apertures *k*, and partly through the apertures *j*. The fuel now passes in the state of spray into the vaporizer *q* which has acquired considerable heat from previously occurring explosions. By reason of the contact of the sprayed 55 charge of fuel with the heated walls of the vaporizer, more or less of the said fuel will become vaporized according to the nature and kind of the fuel, while the non-vaporized and non-sprayed fuel will collect in the lower part 60 of the vaporizer. By this sudden vaporization with constant volume the pressure within the vaporizer will increase considerably, to such an extent that the pressure in the same will be far higher than the highest compression pressure in the cylinder space *f*. This 65

allows of admitting into the interior of the cylinder the charge of vaporized fuel contained in the vaporizer *q*, against the pressure of the body of air contained in the cylinder space *f*. When the piston is on a dead 70 center and is moving down, the valve spindle *s* which is positively actuated as already mentioned moves up and thus opens the apertures *t* and *u* which remain open during a part of the expansion stroke. The fuel vapor remaining in the vaporizer or the non-vaporized residue of the fuel are now expelled. In this expulsion any fuel which has not been atomized and has collected in the lower part 75 of the vaporizer, is now completely converted 80 atomized by the rapidly outflowing vaporized gaseous charge. This completely vaporized gaseous charge in its movement strikes against the table-shaped plate *x*. The latter has a high temperature which is due to 85 the previous combustions and which has been maintained or increased by the compression that has taken place. Consequently the sprayed and for the greater part vaporized charge of fuel will become quickly fully vaporized and will ignite. By reason of the table-shape of the plate *x*, the sprayed fuel charge will spread uniformly in the cylinder space *f* with the result of producing an intimate mingling thereof with the compressed 90 air. During the time that the fuel is being supplied, the pressure in the vaporizer *q* will fall rapidly and the velocity of the gaseous mass that has remained over will gradually lessen, but the vaporization has however 100 taken place already. During the working stroke the air present in the compression chamber is drawn along and flows back through the pipe *d* and the duct *e*, and is conveyed by the parabolic course of the exit 105 aperture and the lateral shoulder *y* to the center of the cylinder space *f*, where its contained oxygen serves to promote the process of combustion. Thus during the working stroke a uniform combustion takes place, and the gases of combustion are expelled during 110 the fourth stroke in the usual manner.

The non-return valve *v* built in the fuel supply duct has for its object to prevent the fuel from flowing back during the compression. In this duct there is also provided a 115 device not shown in the drawing which is connected to the governor and regulates the fuel supply according to requirement.

Instead of a periodical and positive connection between the vaporizing space and the interior of the cylinder, these spaces may be in continuous communication. In such a case the spindle *s* is omitted, and the area of the aperture *u* must be made so small that the compression will be propagated rather in the compression space than in the vaporizer proper. In order to obtain a good regulation of the delivery of fuel in this arrangement, it is preferable to provide a valve in 125 130

the duct *d*. Although the omission of the spindle *s* and of its mechanical actuation constitutes an advantage, yet with the arrangement of a continuous communication between the vaporizer and the interior of the cylinder, the consumption of fuel will be somewhat greater.

In larger sizes of the apparatus the vaporizer *q* will become correspondingly larger, 10 and it might be difficult to produce a greater pressure in it than in the cylinder space. In such a case a small pump is employed which forces the fuel directly into the vaporizer.

The table-shaped plate has for object to 15 insure the ignition of the gaseous mixture if the latter should not have become ignited by the high temperature produced on the compression stroke. If in the herein described arrangement the necessary compression 20 is not obtained, for instance, by reason of want of tightness of the valves, the compression temperature will fall and the ignition will be effected by the said plate *x*. Thus it is only in this case that the plate 25 acts as an igniting device.

Having now particularly described and ascertained the nature of my said invention, and in what manner the same is to be performed, I declare that what I claim is:

30 1. Vaporizing apparatus for liquid fuel internal combustion engines comprising a compression chamber located in the cylinder head and in communication with the cylinder a vaporizer interposed between said 35 compression chamber and the cylinder, means for spraying a charge of liquid fuel into the vaporizer under pressure of the compression chamber, and means for injecting the vaporized charge and liquid residue from

the vaporizer into the cylinder against the 40 pressure of the air charge within the cylinder, substantially as described.

2. Vaporizing apparatus for liquid fuel internal combustion engines comprising a compression chamber in free communication 45 with the cylinder, a liquid fuel duct terminating in an annular space in free communication with the compression chamber, a vaporizer interposed between the cylinder and the said annular space and compression 50 chamber, and a valve automatically operating to establish communication between the vaporizer and the annular space and compression chamber, substantially as described.

3. A liquid fuel internal combustion engine comprising a cylinder, a piston, a compression chamber always in communication with the cylinder, a vaporizer between the chamber and cylinder, a valve closing communication between the vaporizer and cylinder, an annular chamber *n* between the compression chamber and the vaporizer, means for causing fuel to flow into said chamber *n* by the suction working of the piston, means whereby said fluid is sprayed 65 and blown into the vaporizer by means of the compressed air from the cylinder in the compression chamber, and means for opening the valve to allow said fuel to pass into the cylinder. 70

In testimony whereof I have hereunto set my hand in presence of two subscribing witnesses.
